LIFEBOAT

Bernard J. Tegethoff, St. Louis, Mo.

Application February 25, 1942, Serial No. 432,202

8 Claims. (Cl. 9—3)

This invention relates to life boats; and it has special reference to equipment for life boats for preventing the boats from capsizing or turning over in the water and for enabling the boats to sustain heavier loads than other boats of the same tonnage coefficient without the equipment.

Objects of the invention are to provide equipment for attachment to a life boat or other relatively small boat comprising an open frame or cage detachably secured to or about the life boat, and buoyant outriggers or floats hinged to said frame at opposite sides of the boat for movement from approximately vertical unoperated positions at the sides of the boat downwardly to laterally extended positions for use, and vice versa; to provide detachable means for connecting and supporting the outriggers in their vertical unoperated positions at the sides of the boat when they are not in use; and to provide detachable means for connecting the outriggers directly to the boat when they are in their vertical unoperated positions in order to prevent undesired relative movement of the parts.

Another object of the invention is to provide improved equipment for life boats comprising at least two pivotally connected buoyant outriggers having hinged connection to the respective sides of the boat for movement from vertical unoperated positions to outwardly extended positions for use, detachable connections for the two adjacent outriggers for holding them in their unoperated vertically extended positions, detachable connections for the two outer outriggers extending below the boat when the boat is not in use, and an improved open frame or cage for securing the several outriggers to the boat.

Another object of the invention is to provide a plurality of buoyant outriggers having pivotal connection with an attaching frame whereby the outriggers may be moved from upwardly extended unoperated positions which they occupy when not in use, to outwardly extended positions for use, and means for detachably securing the attaching frame to a life boat.

Other objects and advantages of the invention will be apparent from the following description, reference being made to the annexed drawings, in which—

Fig. 1 is a plan view of a life boat of conventional construction having my invention attached thereto.

Fig. 2 is an end elevation showing the present invention applied to a life boat, the parts being in their unoperated positions which they occupy when the boat is not in use.

Fig. 3 is an extended perspective view showing by solid lines the frame and outrigger attachment having the parts extended and showing the outriggers in dotted lines.

The open frame or cage which is constructed for releasable attachment to a boat comprises two duplicate end members. Each end member is preferably composed of a metallic rod bent to form a lower portion 1 having a length approximately equal to the width of the boat for which the device is intended; and two upwardly extended side members 2 arranged to extend upwardly at opposite sides of the boat when the open frame or cage is attached to the boat. When the boat is within the frame or cage, there are two upwardly extended side members 2 at each side of the boat. The upper ends of the side members 2 at each side of the boat are connected by a longitudinal frame member 3 which may be formed integral with the vertical frame members 2 by welding or otherwise. The parts 3 hold the two end frames spaced longitudinally. Longitudinal frame members 4 are secured to the lower portions of the vertical members 3 by eyelets 5 formed on the ends of said members 4 and enclosing the uprights 2, as shown. The frame members 4 may be otherwise attached to the end frames.

The top of the open frame or cage comprises a U-shaped rod including two end arms 6 having eyelets 7 formed on their ends pivotally receiving the longitudinal frame member 3 at one side of the boat; and a longitudinal connecting portion 8 complementary to and arranged to overlie the longitudinal member 3 at the opposite side of the boat (Fig. 3). The longitudinal members 3 and 8 may be attached together by removable and replaceable fasteners 9 extending through registering holes in said members, or said members may be otherwise attached as desired. All of the frame thus described is preferably composed of metallic rods and other metallic parts.

A metallic rod 10 is pivoted to each side member 2 of the frame or cage. As shown, the rods 10 are formed with loops 11 through which the parts 2 extend. Preferably, the loops 11 are below the longitudinal frame members 4. The relative positions of these parts may be reversed if desired. The pivotal connections of the rods 10 with the side members 2 of the frame or cage permit swinging movements of said rods from upwardly extended positions as shown in Fig. 2 to outwardly extended positions as shown in Figs. 1 and 3, and vice versa. A link 12 has pivotal connection 13 with the end of each rod 10 oppo-

site from the loops 11 for swinging movements from outwardly extended positions (Fig. 3) to downwardly extended positions (Fig. 2). A bifurcated combined coupling element and spool 14 is pivotally connected by a number of chain links 15 with the outer end of each link 12 at one side of the frame or cage; and a cooperating coupling element 16 is pivotally connected with the outer end of each link 12 at the opposite side of the cage by links 17. These coupling elements are arranged to be placed in the position shown in Fig. 2 in which the coupling elements 16 are between the forks of the coupling elements 14 and are connected together by removable and replaceable fasteners 18, thus holding the links 12 in proper depending positions.

A buoyant outrigger 19 is attached to the upper sides of each pair of rods 10, one pair of which rods is at each side of the cage or frame and, therefore, at each side of the boat on which the frame is mounted. Similarly, buoyant outriggers 20 are attached to each pair of links 12 outwardly beyond the pivots 13. Abutments 21 are secured to the outer sides of the outriggers 19 for engagement with the adjacent sides of the outriggers 20 when the outrigger devices are in their folded or unoperated positions, as shown in Fig. 2. In such positions, the coupling elements 14 and 16 are attached by the removable and replaceable fasteners 18 to secure the parts in their unoperated positions.

A pair of links 22 are connected with the outer edge of one of the outriggers 19 by pivot linkage 23, and have links or rings 24 adapted to be engaged with fingers 25 attached to and projecting beyond the outer edge of the opposite outrigger 19 (Fig. 2). Thus, the two outriggers 19 will be supported in upwardly extended positions at opposite sides of the boat, as shown in Fig. 2.

A pair of links 26 are pivoted with the fingers 25 by pivot linkage 27 and have links or rings 28 adapted to be engaged with projections 29 attached to the opposite side of the boat. The links 22 and 26 thus cooperate effectively to attach the outriggers at one side of the boat to those at the other side of the boat, and also to the boat proper. Thus, said links 22 and 26 cooperate directly with the coupling elements 14 and 16 to hold all of the elements in proper position when the life boat is not in use.

The life boat may be suspended by a tackle comprising ropes 30 passing over pulleys 31 on davits 32. When the boat is suspended, the rope 30 may be wound on the coupling elements 14-16 which thereby function as spools to hold the ropes. When it is desired to lower the life boat, the fasteners 18 are removed, permitting the rope to slip from the spools provided by the coupling elements 14-16 and the rope to move through or over the pulleys 31. After the boat has been lowered into the water and at any proper time, the links 22 and 26 may be detached from the fingers 25 and the projections 29, respectively. The buoyant outriggers will then extend themselves upon the water substantially to the positions shown in Fig. 1.

The ends of the outriggers 19 may be formed with slots or other hand-holds 33, and the outer edges of the outriggers 20 may be formed with similar slots or hand-holds 34 to be grasped by any persons in the water. The outriggers are of such buoyancy that they will support or assist in supporting one or more persons, and will also increase the buoyancy of the boat proper so that the tonnage coefficient of the boat is considerably

increased. The outriggers may be of solid buoyant material or they may be made hollow, or of any other form desired. Since the outriggers 20 are pivotally connected with the rods 10, it is 5 desirable to prevent said outriggers 20 from becoming folded upon the outriggers 19 when the device is in use on the water. For this purpose, rods 38 may be attached to the outriggers 20 by pivot connections 39. As shown, two rods 38 are 10 provided for each outrigger 20 and are pivotally connected thereto so that, when the device is folded and not in use as in Fig. 2, said rods may be folded against the sides of the outriggers 20 or detached. When the outriggers are extended 15 as shown in Fig. 1, the inner ends of the rods 38 may be detachably connected by linkage 40 with arms 41 attached to the opposite sides of the boat. This will permit necessary swinging movements of the outriggers relative to each other and relative to the boat, and will prevent 20 folding of the outriggers 20 onto the inner outriggers 19. Preferably, each end of the life boat is equipped with a pump 35 which may be operated to discharge water from the boat. Also, each 25 side of the boat is provided with a series of eyelets 36 for engagement by safety belts 37 placed around the respective passengers whereby they may be prevented from falling overboard.

From the foregoing, it is apparent that this 30 invention attains all of its intended objects and purposes. The equipment substantially prevents the boat from capsizing or turning over and considerably increases the tonnage coefficient. Even though the boat itself should be in a leaking condition, these buoyant outriggers will prevent the boat from sinking even when bearing a considerable load. The construction and arrangement of the parts may be varied as widely as the scope of equivalents will permit without departure 35 from the nature and principle of the invention as defined by the appended claims.

I claim:

1. Equipment for boats comprising a frame 45 for attachment to the boat to which the equipment is to be applied and having upwardly extended sides, a pair of arms having pivotal and slid able connection with each of said sides of said frame for swinging movements from upwardly extended to laterally extended positions and vice versa and for vertical sliding movements along said frame, a buoyant outrigger attached to each pair of said arms and movable therewith from upwardly extended to laterally extended 50 positions and vice versa as aforesaid, and a number of links for connecting and holding said outriggers and thereby said arms at opposite sides of said frame in their upwardly extended positions.

2. Equipment for boats comprising a frame 60 adapted to enclose a boat for which the equipment is intended, detachable means extending across the upper portion of said frame for securing the same in connection with the boat, a pair of outwardly extended arms pivotally connected to each side of said frame for swinging movements from upwardly extended to outwardly extended positions and vice versa, a buoyant outrigger attached to each pair of said arms for movement therewith to said positions, buoyant outriggers pivotally connected to the outer 65 ends of said arms for movement from outwardly extended positions when the boat is in the water to downwardly extended positions at the outer 70 sides of said first named outriggers when the 75

boat is not in use, and links for holding said outriggers in said positions.

3. Equipment for boats comprising a frame for enclosing the boat for which the equipment is intended, a pair of pivotally connected outriggers at each side of said frame, means pivotally connecting said pairs of outriggers to said frame for movements from outwardly extended positions to upwardly extended and folded positions at the sides of the boat, links detachably connecting the upper portions of said outriggers across and above the boat and holding the outriggers in their upwardly extended positions, and couplings connecting said outriggers below the boat and cooperating with said links to prevent relative movement of said outriggers.

4. Equipment for boats comprising an open frame, means for securing said frame about the boat to which it is applied, a pair of rods pivoted to each side of said frame for swinging movements from outwardly extended positions to upwardly extended positions and vice versa, a buoyant outrigger attached to each pair of said rods, a pair of links pivoted to the outer ends of each pair of said rods, a buoyant outrigger attached to each pair of said links and movable from outwardly extended positions to approximately vertical positions when said first named outriggers are in upwardly extended positions and vice versa, and couplings for connecting the lower ends of said links below said frame and below the boat.

5. In a life boat, an open frame enclosing the boat, outriggers pivoted to opposite sides of said frame for swinging movements from upwardly extended positions to outwardly extended positions and vice versa, links for connecting one of said outriggers with the opposite side of the boat

at a distance above the upper surface of the boat, and links detachably connecting said outriggers and extending across the plane of the boat and substantially above the same.

6. In a life boat, an open frame enclosing and attached to the boat, a series of outriggers pivotally connected with opposite sides of said frame for swinging movements from upwardly extended to outwardly extended positions and vice versa, and couplings extending below and across the plane of the boat and secured to said outriggers for holding them in their upwardly extended positions.

7. In a life boat, an open frame enclosing and attached to the boat, a series of outriggers pivotally connected with opposite sides of said frame for swinging movements from upwardly extended to outwardly extended positions and vice versa, couplings extending below and across the plane of the boat and secured to said outriggers for holding them in their upwardly extended positions, and series of links detachably connecting said outriggers above the boat and also detachably connecting the outriggers at one side of the boat with the boat proper.

8. Equipment for boats comprising a frame for enclosing a boat for which the equipment is intended, a pair of pivotally connected outriggers at each side of the boat, means pivotally connecting said pairs of outriggers to said frame for movements from outwardly extended positions to upwardly extended and folded positions at the sides of the boat, rods pivotally connected with one outrigger of each pair of outriggers, and links for pivotally connecting said rods with opposite sides of the boat to prevent folding of the outriggers of each pair one upon the other.

BERNARD J. TEGETHOFF.
